(57) CLAIM

The ornamental design for a ski boot cover as shown and described.

DESCRIPTION

FIG. 1 is a top, front, right side perspective view of a ski boot cover of the present design, shown in a closed, fastened position;

FIG. 2 is a top, rear, left side perspective view thereof;

FIG. 3 is a top view thereof;

FIG. 4 is a front, right side perspective view thereof;

FIG. 5 is a top, front, right side perspective view thereof, shown in an open, unfastened position;

FIG. 6 is a top, rear, left side perspective view thereof, also shown in the open, unfastened position; and,

FIG. 7 is a top, rear, right side view thereof, also shown in the open, unfastened position.

The broken lines illustrate portions of the ski boot cover that form no part of the claim.
